(57) **CLAIM**

The ornamental design for a tail light adaptor, as shown and described.

DESCRIPTION

FIG. 1 is a top front perspective view the tail light adaptor; FIG. 2 is a front elevation view thereof;

FIG. 3 is a rear elevation view thereof;

FIG. 4 is a top elevation view thereof, with the bottom elevation view being a mirror image thereof;

FIG. 5 is a right elevation view thereof, with the left elevation view being a mirror image thereof;

FIG. 6 is a section view tail light adaptor, taken along line 6-6 in FIG. 2; and,

FIG. 7 is a top front perspective view of the tail light adaptor, shown in use.

The broken lines shown in the drawings illustrate portions of the tail light adaptor that form no part of the claimed design.
